UNITED STATES PATENT OFFICE.

SIMON W. WARDWELL, OF PROVIDENCE, RHODE ISLAND, ASSIGNOR TO
UNIVERSAL WINDING COMPANY, OF PORTLAND, MAINE.

DESIGN FOR A COP OR THREAD-PACKAGE.

SPECIFICATION forming part of Design No. 35,156, dated October 1, 1901.

Application filed August 19, 1901. Serial No. 72,607. Term of patent 14 years.

To all whom it may concern:

Be it known that I, SIMON W. WARDWELL, a citizen of the United States, residing at Providence, in the county of Providence and State 5 of Rhode Island, have invented and produced a new and original Design for Cops or Thread-Packages, of which the following is a specification, reference being had to the accompanying drawings, forming part thereof.

10 My design is essentially characterized by its substantially spherical or spheroidal form and an equatorial zone or band the surface of which presents an ornamental appearance.

In the drawings, Figure 1 is a side view of 15 a cop or package embodying my design, and Fig. 2 is a perspective view thereof.

The ends or polar zones *a* of the cop or thread-package present a corded configuration disposed in a volute, which starts from 20 a navel-like origin at each pole *b* of the pack-

age, imparting a surface appearance as of a cord laid in a close spiral and covering the surface of the package from the poles to the equatorial zone *c*. The equatorial zone shows a pattern consisting of triangular portions or 25 figures *d*, having their apices opposed to each other, and side portions *e*, filling the spaces between the triangular portions and the polar zones *a*.

What I claim is—

30 The design for a cop or thread-package, substantially as shown.

In testimony whereof I have signed my name to this specification in the presence of two subscribing witnesses.

SIMON W. WARDWELL.
